UNITED STATES PATENT OFFICE

ALBERT NARDONI, OF CHICAGO HEIGHTS, ILLINOIS, ASSIGNOR OF ONE-HALF TO GIOVANNI PUSATERI, OF CHICAGO HEIGHTS, ILLINOIS

CURTAIN BRACKET

Application filed October 29, 1931. Serial No. 571,883.

This invention relates to certain new and useful improvements in curtain brackets.

The primary object of the invention is to provide a curtain bracket wherein the bracket is movably supported on a window frame in a manner to permit lowering movement of the bracket upon the window frame with the curtain and valance supporting cross bars thereof lowered to a position for easy access in the positioning of curtains and valances.

A further object of the invention is to provide a curtain bracket of the foregoing character comprising vertically adjustable side rods carrying cross bars at their upper ends with guide means for the side rods and supports for the lower ends of the side rods to hold the curtain bracket in its upper curtain supporting position relative to the window opening with the side rod guides constituting auxiliary supports for the curtain bracket when the latter is lowered to a position adjacent the lower sash of the window frame for the purpose of conveniently placing curtains upon the cross bars of the bracket.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a front elevational view of a window frame equipped with the improved curtain bracket, the latter being illustrated by dotted lines in its lowered position to facilitate the placing of curtains and the like upon the cross bars thereof;

Figure 2 is a top edge plan view of the window frame with the curtain bracket in position;

Figure 3 is a side edge elevational view of the window frame and curtain bracket;

Figure 4 is a detail sectional view taken on line 4—4 of Figure 1 showing the eye-bolt guide for the side rods of the bracket and a rotatable upper bearing end for the side rods;

Figure 5 is an enlarged fragmentary front elevational view of a portion of the window

frame showing the angle end at the lower extremity of the side rods of the curtain bracket and the bracket support for the end of the rod; and

Figure 6 is a fragmentary elevational view, 55 similar to Figure 5, showing the side rod elevated from engagement with the supporting bracket and rotated as illustrated by dotted lines to dispose the angle end of the rod laterally of the supporting bracket to permit 60 lowering movement of the rod.

Referring more in detail to the accompanying drawing, the reference numeral 10 designates a window frame having sliding sashes 11 therein, the curtain bracket being 65 vertically adjustable upon the window frame to occupy one position in which the curtain supporting cross bars of the bracket are disposed adjacent the upper end of the frame, and another position where the cross bars are 70 lowered as illustrated by dotted lines in Figure 1, to facilitate the mounting of curtains and the like upon the cross bars without resorting to the use of step ladders or other devices.

The curtain bracket comprises a pair of side rods 12, one associated with each side of the window frame 10 and guided for vertical movement over the window frame by a pair of eye-bolts 13 and 14 disposed approximately midway the upper and lower ends of the window frame.

A pair of curtain supporting bars 15 and 16 is carried by the upper ends of the side rods 12, the cross bars 15 and 16 being formed of telescoping sections to accommodate the curtain bracket to windows of different widths, the outer ends of the cross bars 15 and 16 being reversely curved as at 15a and 16a and provided upon their ends with bearing disks 17 and 18 respectively that are received on the upper reduced end 12a of the side rods with the reduced ends 12a rotatable in the bearing disks 17 and 18. A spacing collar 19 separates the bearing ends 17 and 18 and each reduced end 12a is threaded for the reception of a retaining nut 20 for the ends of the cross bars.

The lower end of each side rod 12 is bent at right angles to provide a side arm 21, the 100

outer end of which is bent downwardly as at 22 to provide a finger for reception in the loop bracket 23 anchored as at 24 to the sides of the window frame.

5 When the curtain bracket is in the full line position illustrated in Figure 1, the side arms 21 upon the lower end of each rod 12 is supported upon the loop bracket 23 with the depending finger 22 extending through the bracket and when so disposed, the cross bars 15 and 16 for the support of curtains and the like are arranged adjacent the upper end of the window frame. When it is desired to remove or replace the curtains upon the cross bars, the side rods 12 are elevated to disengage the fingers 22 from the loop brackets 23 to the full line position shown in Figure 6, the side rods 12 being then rotated to cause the side arms 21 to assume the dotted line position shown in Figure 6, this rotation of the side rods being permitted by the upper bearing ends 12a and at which time the side rods 12 may be lowered to the dotted line positions shown in Figure 1 with the bearing disks 18 of the cross bar 16 supported upon the upper eye-bolt 14, the curtain bracket then being conveniently positioned for easy attachment thereto of the curtain. The curtain bracket is restored to the full line position illustrated in Figure 1 by raising the side rods 12, rotating the same and projecting the fingers 22 upon the side arms 21 through the loop brackets 23.

35 While there is herein shown and described the preferred embodiment of the invention, it is nevertheless to be understood that minor changes may be made therein without departing from the spirit and scope of the invention as claimed.

I claim:

1. In a curtain bracket of the character described, a pair of side rods, curtain supporting cross bars at the upper ends thereof, a laterally directed arm at the lower end of each side rod, and a depending finger at the outer end of the arm.

45 2. For mounting on a window frame having a pair of vertically alined eye-bolts at each side thereof approximately midway the upper and lower ends thereof, a curtain bracket including side rods slidably guided in the eye-bolts, curtain supporting cross bars at the upper ends of the side rods, through which the upper ends of the rods are journalled and said bearing ends of the cross bars adapted to be supported on the upper eye bolts when the bracket is in lowered position, and bracket supports on the window frame for the lower ends of the side rods when the curtain bracket 50 is in raised position.

55 3. For mounting on a window frame having a pair of vertically alined eye-bolts at each side thereof approximately midway the upper and lower ends thereof, a curtain bracket including side rods slidably guided in the

70 eye-bolts, curtain supporting cross bars at the upper ends of the side rods, through which the upper ends of the rods are journalled and said bearing ends of the cross bars adapted to be supported on the upper eye bolts when the bracket is in lowered position, and bracket supports on the window frame for the lower ends of the side rods when the curtain bracket 75 is in raised position, each bracket support including a loop member and the lower end of each side rod carrying an angle end to be alined with the bracket loop for passage therethrough upon rotation of the side rods.

4. For mounting on a window frame having a pair of vertically alined eye-bolts at each side thereof, approximately midway the upper and lower ends thereof, a curtain bracket 80 including side rods slidably guided in the eye-bolts, curtain supporting cross bars at the upper ends of the side rods, through which the upper ends of the rods are journalled and said bearing ends of the cross bars adapted to be supported on the upper eye bolts when the bracket is in lowered position, and bracket supports on the window frame for the lower 85 ends of the side rods when the curtain bracket is in raised position, each bracket support including a loop member, a laterally directed arm on the lower end of each side rod adapted for support upon the loop member and a depending finger extension on the lateral arm to be alined with the loop member for passage therethrough upon rotation of the side 90 rod.

95 In testimony whereof I affix my signature.

ALBERT NARDONI.
